UNITED STATES PATENT OFFICE.

LEON MILTIADES MESSINESI, OF LONDON, ENGLAND, ASSIGNOR TO THE
DIAGONAL AND UNIVERSAL WOOD WORKING MACHINE COMPANY,
LIMITED, OF SAME PLACE.

WOODWORKING MACHINERY.

SPECIFICATION forming part of Letters Patent No. 663,182, dated December 4, 1900.

Application filed July 1, 1899. Serial No. 722,591. (No model.)

To all whom it may concern:

Be it known that I, LEON MILTIADES MESSINESI, a subject of the King of Greece, residing at London, England, have invented new and 5 useful Improvements in Woodworking Machinery, (for which I have applied for a patent in Great Britain, No. 11,164, dated May 29, 1899,) of which the following is a specification.

This invention relates to apparatus for sawing, planing, drilling, turning, and otherwise working wood.

In the accompanying drawings, Figure 1 is a side elevation of apparatus made according to the invention. Fig. 2 is a front view thereof. Fig. 3 is a sectional plan of the apparatus, and Fig. 4 is a vertical section through the lower part of the apparatus.

a is the frame or support of the apparatus, the said frame being provided with an upper 20 horizontal arm a'. The lower or main portion of the frame carries a table consisting of the bed-plate b, on which slides the frame b', and of the auxiliary frame c, which is pivoted at c' to the frame b', so as to swing in a vertical 25 plane, and of the table proper, d, which is adapted to slide horizontally in a direction at right angles to that in which the frame b' slides on the bed-plate b. The frame b is adjusted in height by means of the rack b² and 30 the pinion b³, mounted upon the spindle b⁴, and adapted to be operated by the worm-wheel b⁵ and worm b⁶, mounted upon the spindle b⁷, the latter having a squared end to receive an operating-handle.

35 To operate the frame b', a screw e is provided, which is fixed in lugs e' e' on the frame b' and engages an internally-screw-threaded bevel-wheel f, gearing with a bevel-wheel f', keyed upon a spindle f², mounted in a bearing secured to the frame b, the said bevel-wheel f being retained in position by a lug f³, secured to the frame b, so that by rotating the spindle f² the bevel-wheel f' rotates the bevel-wheel f, thereby feeding the sliding table in either direction, as desired.

40 To adjust the table to any desired inclination, the following arrangement is made use of—that is to say, one side of the said auxiliary frame has fitted to it a toothed sector c², 45 with which gears a worm c³, mounted upon a

spindle c⁴, adapted to be operated by hand through the medium of the bevel-wheel c⁵ upon the said spindle, which bevel-wheel gears with a second bevel-wheel c⁶, mounted upon a spindle c⁷, supported in a bearing c⁸ on the 55 sliding frame b' and adapted to be rotated by a suitable handle which can be fitted upon its squared end. The center of the sector c² coincides with the axis c', around which the auxiliary frame c swings. With this arrangement it will be obvious that by turning the worm-spindle c⁴ the sector c² is rotated, thereby turning the work-table proper, d, to the desired position.

To enable the auxiliary frame c to be 60 clamped in any position to which it may be adjusted, the toothed sector c² has a curved slot c⁹ formed in it, (the curve having the pivot c' as a center,) and a rod g is passed through the said slot, the said rod g extending through the apparatus to the other side of the table and through a slot in a similar but untoothed sector g', attached to the other side of the table. The end projecting through the sector g' is provided with a head g², and the 70 other end is screw-threaded so as to receive a screw-threaded nut or handle g³, which when tightened upon the said screw-thread securely holds the table in the position to which it may be adjusted.

The work-table proper, d, is provided with the usual under-cut grooves d' for the guides and clamps and is adapted, as above mentioned, to slide horizontally upon the auxiliary frame c, the adjustment being effected by the 75 usual arrangement of screw-rod and nut.

In some cases the work-table proper, d, can be dispensed with and replaced by a slide, to which the work can be clamped and which can be slid by hand in a groove in the auxiliary frame c. The toothed sector c² can also be replaced by a plain sector, in which case the inclination of the table is adjusted by hand, the worm being no longer necessary. The table may also be provided with grooves d² 80 d³, as shown, or with edge grooves to receive adjustable stops which project over the table and serve for establishing the position upon the table of successive pieces of similar work to be similarly treated.

The upper horizontal arm a' of the frame carries a spindle h , which is adapted to be rotated therein and to carry a tool at its front end—for example, a saw i , a drill, &c. The 5 arm a' is also provided at its upper part with a work-table j , so placed that it can present work to the upper part of the saw i . The said table j is mounted on a guide on the upper part of the said arm a' in such a manner that 10 it can be slid back out of operation to make place for other tools. A hanging bracket can also be provided for being fitted to the under part of the arm a' , the said hanging bracket being adapted to receive one end of a spindle, 15 the other end of which is carried in one end of the short shaft l , which is mounted in bearings l' in the arm a' and is adapted to be rotated as hereinafter described. This spindle is arranged to receive single tools, such as 20 beading-tools, routing-cutters, chisels, or drills set in a horizontal position. With this arrangement of two tool-spindles arranged one above the other it is possible to submit work to two successive operations—such, for 25 example, as sawing and grooving—by first raising the work-table set at the required angle, so that the work is cut by the saw mounted upon the upper spindle, and then simply lowering the said table (without altering its 30 angle) to enable the work to be grooved (or otherwise treated) by the tool upon the lower spindle.

The apparatus is driven by a shaft m , mounted in bearings m' in the lower part of 35 the frame a , the said shaft being provided with fast and loose pulleys n n' , whereby it can be operated from any suitable source of power, and with a pulley o for driving the upper and lower spindles h and l , respectively; 40 by means of belts, either one of which can be placed in position according as it is required to drive the upper or lower spindle through the medium of their pulleys n^2 n^3 . By this means the disadvantage of having more than 45 one belt on the machine at a time is obviated. The driving-shaft is provided with a friction-wheel p , with which a second friction-wheel p' , mounted upon a shaft q , is brought into contact by means of the counterweighted 50 pedal q' , which is pivoted at q^2 and is provided with a fork q^3 , which engages a sleeve q^4 , secured to the boss of the friction-wheel p' , so that the rotation of the shaft m effects 55 the rotation of the shaft q , the end of which is provided with a crank r , having a crank-pin r' , which on the rotation of the shaft reciprocates a fret-saw slide s through the medium of the connecting-rod r^2 . This slide s is held in guides s' and has attached to its 60 two ends a flexible fret-saw t , which when required to be used is passed over pulleys u u' u^2 (shown only in dotted lines in the drawings) and which will be suitably secured to the apparatus. By depressing the pedal q' the friction-wheels are disengaged and the saw remains at rest. Slots u^3 u^4 are formed in the

table proper, d , for the passage of the saw at different inclinations of the table.

Having now particularly described and ascertained the nature of my said invention and 70 in what manner the same is to be performed, I declare that what I claim is—

1. In a woodworking apparatus, the combination with the main support, of a bed-plate, means for vertically adjusting said bed-plate, 75 a sliding frame mounted on said bed-plate, means for horizontally adjusting said sliding frame, an auxiliary frame swiveled to the forward part of said sliding frame, means for adjusting said auxiliary frame, a table upon 80 said auxiliary frame, means for adjusting said table, a forwardly-extending arm integral with said support, a spindle mounted in the vertical portion of said arm, means for operating said spindle, a spindle mounted in 85 the forwardly-extending horizontal portion of said arm and means for operating said spindle, a fret-saw and means for operating said saw, substantially as described.

2. In a woodworking apparatus, the combination with the main support, of a bed-plate, means for vertically adjusting said bed-plate, 90 a sliding frame mounted on said bed-plate, means for horizontally adjusting said sliding frame, an auxiliary frame swiveled to the forward part of said sliding frame, means for adjusting said auxiliary frame, a table upon 95 said auxiliary frame, means for adjusting said table, a forwardly-extending arm integral with said support, a spindle mounted in 100 the vertical portion of said arm, means for operating said spindle, a spindle mounted in the forwardly-extending horizontal portion of 105 said arm and means for operating said spindle, a fret-saw, means for reciprocating said saw and means for throwing said reciprocating device into and out of engagement with the driving mechanism, substantially as described.

3. In a woodworking apparatus, the combination with the main support, of a bed-plate, means for vertically adjusting said bed-plate, 110 a sliding frame mounted on said bed-plate, means for horizontally adjusting said sliding frame, an auxiliary frame swiveled to the forward part of said sliding frame, means for adjusting said auxiliary frame, a table upon 115 said auxiliary frame, means for adjusting said table, a forwardly-extending arm integral with said support, a spindle mounted in 120 the vertical portion of said arm, means for operating said spindle, a spindle mounted in the forwardly-extending horizontal portion of 125 said arm and means for operating said spindle, a fret-saw, means for reciprocating said saw and means for throwing said reciprocating device into and out of frictional engagement with the driving mechanism, substantially as described.

4. In a woodworking apparatus, the combination with the main support, of a bed-plate, means for vertically adjusting said bed-plate, 130

a sliding frame mounted on said bed-plate, means for horizontally adjusting said sliding frame, an auxiliary frame swiveled to the forward part of said sliding frame, means for adjusting said auxiliary frame, a table upon said auxiliary frame, means for adjusting said table, a forwardly-extending arm integral with said support, a spindle mounted in the vertical portion of said arm, means for operating said spindle, a spindle mounted in the forwardly-extending horizontal portion of said arm and means for operating said spindle, a fret-saw, means for reciprocating said saw, a shaft operating said reciprocating device, a bevel friction-wheel loosely keyed to said shaft, an annular collar integral with said bevel friction-wheel and provided with an annular groove and a counterweighted pedal provided with a bifurcated arm adapted 20 to engage said annular groove in said collar, substantially as described.

5. In a woodworking apparatus, the combination with the main support, of a bed-plate, means for vertically adjusting said bed-plate, 25 a sliding frame mounted on said bed-plate, means for horizontally adjusting said sliding frame, an auxiliary frame swiveled to the forward part of said sliding frame, means for adjusting said auxiliary frame, a table upon 30 said auxiliary frame, means for adjusting said table, a forwardly-extending arm integral with said support, longitudinal grooves formed on two sides of the extreme forward end of said arm adapted to receive tools, a 35 spindle mounted in the vertical portion of said arm, means for operating said spindle, a spindle mounted in the forwardly-extending horizontal portion of said arm and means for operating said spindle, a fret-saw and 40 means for operating said saw, substantially as described.

6. In a woodworking apparatus, the combination with the main support, of a bed-plate, means for vertically adjusting said bed-plate, 45 a sliding frame mounted on said bed-plate, means for horizontally adjusting said sliding frame, an auxiliary frame swiveled to the forward part of said sliding frame, means for adjusting said auxiliary frame, a table upon 50 said auxiliary frame, means for adjusting said table, a forwardly-extending arm inte-

gral with said support, a table provided on top of said arm, a spindle mounted in the vertical portion of said arm, means for operating said spindle, a spindle mounted in the 55 forwardly-extending horizontal portion of said arm and means for operating said spindle, a fret-saw and means for operating said saw, substantially as described.

7. In a woodworking apparatus, the combination with the main support, of a bed-plate provided with a downwardly-extending portion, a rack on said downwardly-extending portion, a gear-wheel meshing with said rack, a worm-wheel and worm rigidly mounted on 60 the shaft with said gear-wheel, means for operating said worm, a sliding frame adapted to be shifted on said bed-plate, a long screw rigidly secured to said sliding frame, a pinion provided with a screw-threaded opening 65 for engaging said long screw, means for preventing the longitudinal movement of said pinion, an operating-pinion gearing with said first-mentioned pinion, means for turning 70 said operating-pinion, an auxiliary frame 75 swiveled to said sliding frame, segments integral with said auxiliary frame, slots concentric with the swiveling point, a long bolt secured to the sliding frame and passing through said slots and means of tightening 80 said bolt, a table adapted to slide on said auxiliary frame, a long screw and nut for adjusting said table, a fret-saw, a slide attached to said saw, guides for said slide, a 85 crank-pin, a rod pivotally connected to said 85 slide and said crank-pin, a shaft operating said crank-pin, a bevel friction-wheel loosely keyed to said shaft, a collar integral with said friction-wheel and provided with an annular groove, a counterweighted pedal provided with a bifurcated arm adapted to engage said annular groove in said collar, a 90 bevel-wheel on the driving-shaft to gear with said friction-wheel, and a forwardly-extending arm integral with said support and provided with suitable tool-carrying spindles, 95 substantially as described.
